UNITED STATES PATENT OFFICE

GREGOR H. GLITZKE, OF KANSAS CITY, MISSOURI

SEALING MEANS FOR PERFORATED CONTAINER CAPS

Application filed February 27, 1928. Serial No. 257,310.

The present invention relates to closure constructions for receptacles, such as cans, bottles, jars and the like, and particularly to containers from which the contents are designed to be discharged by shaking the container and allowing the contents to escape by way of openings or perforations provided in the cap or closure element.

The principal object in view is to provide a closure cap or element of this character having the usual spraying or sifting openings or perforations, together with means for temporarily sealing such openings or perforations until such time as it is desired to use

the contents thereof.

With this object in view, I provide a liner disk or diaphragm within the cap or closure element, in position to seal the openings or perforations thereof, said liner or diaphragm element being of suitable frangible material in order that the same may be readily punctured for allowing the contents of the container to be ejected through the spraying or sifting openings in the cap or closure element.

In carrying out the invention in practice, I provide a second perforated disk adapted to fit inside the cap or closure element with its openings in register with the openings in the cap element and acting to hold the liner or diaphragm element in snug fitting relation against the inner face of the cap.

With the foregoing objects in view, the invention will now be described by reference to the accompanying drawing illustrating a suitable and practical form of construction for embodying the proposed improvement, after which the features deemed to be novel will be set forth and claimed.

40 In the drawing:—

Figure 1 is a perspective view showing a container provided with a cap or closure element equipped with the present improvement; and

45 Figure 2 is a transverse detail sectional view of said cap or closure element, and illustrating the interior construction comprising the improvement.

50 Referring now to said drawing in detail, this shows the invention embodied in a clo-

sure or cap element 3 of common construction having the marginal flange portion 4 for embracing the neck portion of a container, which may be a bottle, can, or any other desired form of receptacle such as a jar having 55 any suitable form of thread or other expedient (not shown) adapted for retaining engagement with marginal inturned portions 6 provided on the flange 4 of the cap; such retaining means forms no part of the present 60 invention, which is concerned only with the improved means for temporarily sealing the perforations or openings 7 of the main body portion of the cap element 3.

For this purpose, I provide a suitable liner 65 or diaphragm type of disk 8 of a size adapted to fit snugly within the flange portion 4 and against the interior face of the body portion thereof and hence in sealing relation to the openings 7, as clearly shown in Figure 2, 70 This disk or diaphragm element 8 is of suitable frangible material, adapted to be readily punctured by means of a suitable pointed instrument 9 as represented in Figure 2. For facilitating such punching operation, as well 75 as for assisting in maintaining the diaphragm or disk 8 in the position illustrated, that is, in sealing relation to the openings or perforations 7, a second disk or wafer 10 is provided of substantially the same size as the disk or 80 diaphragm 8 and fitting snugly against the latter within the flange 4, this second disk 10 being also provided with one or more openings 12, corresponding to the openings 7 and 85 in position to accurately register with said openings 7 as shown in Figure 2. By this means, it is apparent that by use of the tool or instrument 9, little effort is required for effecting the punching of the portions of the disk or diaphragm 8 which are embraced between the registering openings 7 and 12 and a more effective punching action is produced 90 due to the cooperating openings in registered relation. In this way, the openings 7 are unsealed, and the contents of the jar or can 95 may be sprayed or sifted out through said openings 7 in the usual way.

The improvement thus provides a very simple and yet inexpensive and efficient means for the temporary sealing of perforated caps 100

3 and until such time as their use is desired, and while I have illustrated in the drawing the use of a plurality of the perforations 7, it is apparent that this number is unessential, and the cap 3 may be provided with but 5 one such opening, or as many as may be desired; it being only necessary that the interior disk 10 be provided with one or more openings in such position as to register the 10 same with the outer openings 7 of the cap.

10 While I have illustrated and described what I now regard as the preferred form of embodying the improvement, I desire to reserve the right to make such changes and 15 modifications as may fairly fall within the scope of the appended claims.

Having thus described my invention, what I claim and desire to secure by Letters Patent is:—

- 20 1. A cap structure for containers comprising a perforated cap element adapted to be removably fitted to the container, a perforated disk secured inside the cap and having perforations of the same size as the perforations of said cap element and in registered relation therewith, and a closure element comprising an imperforate disk or diaphragm of frangible material embraced between said first disk and cap element and sealing the perforations thereof.
- 25 2. A container top provided with one or more perforations, a disk located inside said top and provided with one or more perforations of the same size as the perforations of 30 the top and registering therewith, and a closure element comprising an imperforate disk or diaphragm of frangible material retained in place between said first disk and the inside of the top for temporarily sealing the 35 perforations thereof.
- 30 40 2. In witness whereof I hereunto affix my signature.

GREGOR HENRY GLITZKE.
